UNITED STATES PATENT OFFICE.

HAROLD SIMMONDS DAVIS AND MARY DAVIDSON DAVIS, OF PITTSBURGH, PENNSYLVANIA.

APPARATUS FOR THE ESTIMATION OF VAPOR-PRESSESSES.

1,318,362.

Specification of Letters Patent.

Patented Oct. 14, 1919.

Application filed January 31, 1919. Serial No. 274,228.

To all whom it may concern:

Be it known that we, HAROLD S. DAVIS and MARY D. DAVIS, residing at Pittsburgh, Allegheny county, Pennsylvania, have invented a new and useful Improvement in Apparatus for the Estimation of Vapor-Pressures, of which the following is a full, clear, and exact description, reference being had to the accompanying drawings, forming part of this specification, in which—

Figure 1 is a front elevation partly broken away of one form of apparatus embodying our invention; and

Fig. 2 is a section on the line II—II of Fig. 1.

Our invention has relation to apparatus for use in the estimation of vapor pressures. It is designed to provide a simple and convenient form of apparatus which can be used for the purpose of carrying out the method of quantitative estimation of vapors in gases described and claimed in our Patent No. 1,272,922, dated July 16, 1918, as well as for other purposes, some of which are hereinafter referred to.

The nature of the present invention will be best understood by reference to the accompanying drawing, in which we have shown the preferred form thereof and which will now be described, it being premised, however, that the particular form of apparatus which we have illustrated may be widely varied in detail, without departing from the spirit and scope of our invention as set forth in the appended claims.

In this drawing, the numerals 2 and 3 designate two similar necked flasks, preferably of about 150 to 300 cubic centimeters capacity each. These flasks are connected by a manometer tube 4, whose ends are sealed into the necks of the respective flasks, as indicated at 5. The two flasks are preferably located relatively close together, so as to permit of their immersion, when necessary, in a constant temperature bath, and the manometer tube is preferably so shaped and arranged as to be offset from the flasks in a manner to enable it to stand outside of the bath when the flasks are immersed. Each of the flasks is tightly closed, preferably by a ground glass stopper 6, which is capable of making an air-tight joint. Each branch of the manometer tube is preferably provided with the stop cock 7, by means of which the pressures in the

two flasks may be brought to atmospheric pressure and thus equalized. One of the branches is also preferably provided with a second stop cock 8, to facilitate the evacuation of the flask.

Each of the stoppers 6 is shown as having therein a tube 9, passing vertically therethrough, with a metal rod 10 extending slidably through such tube. At their lower ends, these rods project downwardly into the respective flasks 2, and 3, and attached to the lower end of each rod is a small sealed glass bulb 11, which is preferably formed with a thin bottom, so as to be readily breakable, and which contains sealed up within it, some of the substances whose vapor is to be determined. The upper end portion of each rod has secured thereto a push member 12, which seats within the upper end portion of a piece of flexible rubber tube 13, whose lower end seats over the upper end of the tube 9.

The rubber tube makes a tight fit at its end portions, and the joints may be made tight in any suitable manner, as by the use of vacuum grease and wire wrapping, such as indicated at 14.

The manometer tube may be filled with mercury or any suitable liquid, and is provided with a scale 15, upon which any difference in pressure in the two flasks may be directly read. When mercury is used for the manometer liquid, one millimeter is a convenient size for the bore of the manometer tube.

The actual dimensions of any parts of the apparatus may be varied within wide limits; but in order to obtain accurate results quickly, it is essential that when the sealed bulb is broken in the bottom of the flask, its vapor should be able to quickly penetrate throughout the interior of the flask. Therefore, local pockets in the interior surfaces in which the vapor would diffuse but slowly should be avoided, and all connecting tubes should have a small volume compared with the total volume of the flasks.

The sealed bulbs may be readily broken by pushing down the upper end of the metal rods 10, the rubber tubes 13 yielding enough to permit the bulbs with their thin bottoms to be forced into breaking contact with the bottom wall of the flask.

One method of using the apparatus for the quantitative estimation of vapors in

gases is described and claimed in our patent above referred to, and to which reference may be had.

The apparatus may also be used for 5 various other purposes, some of which are as follows:

(1) For the measurement of the vapor pressure of a substance, either liquid or solid, at any one temperature.

10 (2) For the measurement of the vapor pressure of a substance, either liquid or solid, at various temperatures.

In this case, the procedure is as follows:

15 The pressures in the two flasks are equalized at the highest temperature by opening and closing the stop cocks, to thereby bring the pressure in each flask to atmospheric. The bulb containing the substance in question is then broken in the flask at one side. 20 When the pressure is fully developed, it is read from the manometer. The apparatus is then brought to the next highest temperature. The air pressures will necessarily compensate and the vapor pressure of the 25 substances at this temperature can be read from the manometer.

The operations are repeated for as many 30 temperatures as desired. It is preferable to start with the highest temperature, so that the total pressures in the flasks will be continuously decreasing, thereby lessening the danger of leakage.

35 (3) For the measure of the vapor pressure from the solution of a volatile substance in a non-volatile substance.

This may be obtained by having in the 40 bottom of the flask some of the non-volatile substance and breaking into it a bulb containing the volatile substance. For instance, the vapor pressure of benzene from wash 45 oil can be found by breaking the bulb containing a known weight of benzene into a known weight of wash oil in one flask.

It will be noted that other gases than air 45 may be used in the flasks and that the pressures may be regulated in various ways.

We claim:

1. Apparatus for the estimation of vapor 50 pressures comprising two similar flasks connected by a manometer, and a fragile container adapted to be inserted into one of said flasks, and a carrier for supporting the container in the flask having means whereby said container may be broken within said 55 flask, substantially as described.

2. Apparatus for the estimation of vapor 60 pressures, comprising two similar flasks connected by a manometer, and having openings in their necks, and removable closures for said openings which provide means for

introducing fragile containers into the flasks, said closures having means whereby the containers may be broken within the flasks, substantially as described.

3. Apparatus for the estimation of vapor 65 pressures comprising two flasks having necks connected by a manometer tube and having removable tight-fitting stoppers, a vertically movable member seated in each of said stoppers and adapted to support a fragile container at its lower end portion, and means for sealing the flasks against the entrance of air past said members, substantially as described.

4. Apparatus for the estimation of vapor 75 pressures, comprising two flasks, a manometer connecting said flasks, and having means for equalizing the pressures therein, said flasks having openings, and removable closures for sealing said openings, said closures having means whereby a fragile container 80 may be broken within the flasks without removing or unsealing the closures, substantially as described.

5. Apparatus for the estimation of vapor 85 pressures, comprising two sealed flasks connected by a manometer tube, said tube being offset from the flasks, and removable closures for said flasks, said closures having means whereby a container may be introduced into and broken within the flasks, 90 substantially as described.

6. Apparatus for the estimation of vapor 95 pressures, comprising two sealed flasks connected by a manometer tube, said tube having means for evacuating the flasks and also for equalizing the pressures therein, and removable closures for said flasks, said closures having means whereby a fragile sealed container may be introduced into and broken 100 within the flasks, substantially as described.

7. Apparatus for the estimation of vapor 105 pressures comprising two flasks connected by a manometer tube, each of said flasks having a tight-fitting removable stopper, a tube extending through the stopper, a vertically movable rod seated in the tube, and a flexible member forming a seal for the joint between the rod and tube, substantially as described.

8. Apparatus for the estimation of vapor 110 pressures comprising two flasks connected by a manometer, means for equalizing the pressures within the flasks, and a vertically movable container carrier extending into each 115 flask, substantially as described.

In testimony whereof, we have hereunto set our hands.

HAROLD SIMMONDS DAVIS.
MARY DAVIDSON DAVIS.
